US0D1055912S

(12) **United States Design Patent** (10) **Patent No.:** **US D1,055,912 S**
(45) **Date of Patent:** **** Dec. 31, 2024**

(54) **DISPLAY DEVICE**

(71) Applicant: **Samsung Display Co., Ltd.**, Yongin-si (KR)

(72) Inventors: **Ho Yeon Yu**, Yongin-si (KR); **Hyeon Sook Jeong**, Yongin-si (KR); **Hyun Gu Kim**, Yongin-si (KR)

(73) Assignee: **Samsung Display Co., Ltd.**, Yongin-si (KR)

(**) Term: **15 Years**

(21) Appl. No.: **29/853,642**

(22) Filed: **Sep. 16, 2022**

(30) **Foreign Application Priority Data**

Mar. 16, 2022 (KR) 30-2022-0010238

(51) **LOC (14) Cl.** **14-03**

(52) **U.S. Cl.**

USPC ..... **D14/138 AB**

(57) **CLAIM**

The ornamental design for a display device, as shown and described.

DESCRIPTION

FIG. 1 is a perspective view of the display device according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the display device shown in an alternate configuration; and,

FIG. 9 is a perspective view of the display device shown in another alternate configuration.

In the drawings, the broken lines illustrate portions of the display device that form no part of the claimed design.

1 Claim, 9 Drawing Sheets
